COMBINED FLUID AND ELECTRICAL CONNECTOR

Charles J. Pauler, St. Paul, Minn., and Russell B. Waddell, Jr., Waynesville, N.C., assignors to Whirlpool Corporation, a corporation of Delaware

Filed Dec. 9, 1959, Ser. No. 858,497

2 Claims. (Cl. 339—16)

This invention relates to a vacuum cleaner hose assembly in which there is provided a flexible hose for conducting dirt laden air from a cleaning tool such as a floor nozzle to a suction and filter unit in which the dirt is filtered from the air and the air is exhausted to the atmosphere.

One common type of vacuum cleaner employs a unit for creating a vacuum and filtering dirt from dirt laden air drawn into the unit by reason of the vacuum. This unit is connected to a cleaning tool such as a floor nozzle by means of a movable conduit including as a portion thereof a flexible hose. It has been proposed that the floor unit in certain instances be a device having an electric motor used to rotate a brush. Thus, such a device is intended to function in its cleaning operation in somewhat the same manner as the ordinary stick type cleaner, although in the ordinary stick type cleaner the motor brush suction unit and the vacuum creating and dirt filtering unit are carried on the common wheel mounting.

An electrically operated floor unit of the above type is disclosed and claimed in C. H. Sparklin et al. application Serial No. 697,239, filed November 18, 1957, and assigned to the same assignee as that for the present invention. A vacuum cleaner of the type that is adapted to be connected by means of a flexible hose to a floor tool and the like is disclosed in C. E. Hanson application Serial No. 685,977, filed September 24, 1957, and also assigned to the same assignee as the present invention.

In order to supply such a motor operated floor tool and the like with an electric current it has been proposed that the flexible air hose interconnecting the suction unit and the motor operated floor tool incorporate an electric cord built into the hose and arranged in a helix therearound. The electric cord in these instances is actually a part of the hose and is not visible from the exterior or the interior of the hose. In these instances one end of the electric cord is adapted to be connected to a power source in the suction unit while the other end of the cord is adapted to be connected to the motor of the floor tool in order to supply electric current thereto.

The present invention provides an improved connector assembly for a vacuum cleaner hose including improved releasable means for connecting the ends of the hose and its incorporated electric cord to the suction unit and the floor tool respectively.

One of the features of this invention is to provide an improved vacuum cleaner hose assembly comprising a hose, an electric cord associated with the hose, a coupler on the end of the hose for attachment of the assembly to a vacuum cleaning apparatus, an electrical connector to which the cord is attached, and means attaching the electrical connector to the coupler whereby strain on the connector will be absorbed by the coupler instead of the cord.

Another feature of the invention is to provide such a vacuum cleaner hose assembly further including an enclosure enclosing the end of the hose and at least a portion of the connector.

Other features and advantages of the invention will be apparent from the following description of certain embodiments thereof taken in conjunction with the accompanying drawings. Of the drawings:

FIGURE 1 is a fragmentary perspective view of a vacuum cleaner apparatus provided with a hose assembly embodying the invention.

2

FIGURE 2 is an enlarged elevation of one end of the hose assembly.

FIGURE 3 is a diametric section thereof, in secured association with a portion of the suction unit.

FIGURE 4 is a plan of the coupler and electrical connector subassembly with a portion of the hose associated therewith.

FIGURE 5 is an elevation thereof, a greater extent of the hose being illustrated.

10 FIGURE 6 is a fragmentary view partially in section and partially in elevation of the opposite end of the vacuum cleaner hose assembly.

FIGURE 7 is a transverse section taken substantially along the line 7—7 of FIGURE 6.

15 FIGURE 8 is a fragmentary elevation of another form of an end of a vacuum cleaner hose assembly embodying the invention.

In the embodiment of the invention shown in FIGURES 1 through 7, a vacuum cleaner hose assembly generally designated 10 includes a flexible hose 11 which may be formed of a plastic such as polyethylene and having associated therewith a pair of wires 12, the precise hose construction per se forming no part of the instant invention. A first coupler 13 is connected to one end of the hose 11 for coupling that end of the hose to an intake 14 of a suction unit 15. A male electrical connector 16 is carried on the coupler 13 and is electrically connected to wires 12. The suction unit 15 is provided with a complementary female electrical connector 17 adjacent the intake 14 for electrically conductive connection with connector 16 when coupler 13 is installed in intake 14.

The opposite end of the hose is provided with a coupler 18 adapted to be telescopically installed in a tubular end 19 of a floor tool (not shown). Coupler 18 carries a female connector 20 which has electrically conductive connection with a complementary male connector 21 carried on floor tool end 19 when the coupler 18 is installed in end 19. Connector 21 is connected by a suitable electrical cable 22 to the brush motor (not shown) of the floor tool. Thus, when the hose assembly 10 is connected between suction unit intake 14 and floor tool end 19 an electrical connection from the suction unit to the floor tool is provided for operation of the floor tool motor.

Turning now more specifically to FIGURES 2 through 5, coupler 13 includes a tubular hose supporting portion 23 provided with a plurality of outwardly extending projections 24 on the outer surface thereof. Projections 24 are arranged in a helix and are aligned in longitudinal rows. The end of hose 11 is received on the surface of hose supporting portion 23 and is held in position by the projections 24 which are aligned beneath adjacent convolutions of the current carrying wires 12. The outer end 28 of hose supporting portion 23 is enlarged and also radially thickened as indicated at 25. This outer end 28 is provided with an annular internal groove 26 and a longitudinal groove 27.

The radially thickened portion 25 of the hose supporting portion 23 is provided with a recess means 29 defining opposed first locking shoulders 30. Held within the recess means 29 is an inner portion 31 of male connector 16 shaped to provide second shoulders complementary to shoulders 30 so that inner portion 31 mates with and fits snugly and securely within the recess 29. These complementary shoulders comprise retaining elements for retaining the connector portion 31. An outer portion 32 of the male connector 16 extends forwardly beyond the end of hose supporting portion 23 with the longitudinal axes of the coupler 13 and of the connector 16 being substantially parallel to each other. Connector 16 is provided with means 33 therein for connecting the ends of the wires 12 to a pair of metal terminal prongs 34 pro-

jecting forwardly from outer portion 32 of the connector 16.

Coupler 13 further includes a tubular attaching portion 35 having an outer end 36 arranged for removable fit in intake 14 of the suction unit 15. The inner end 37 of the coupler attaching portion 35 is reduced in diameter for telescopic fit within outer end 25 of the hose supporting portion 23. A plurality of circumferentially spaced ears 38 are struck from the inner end 37 of the attaching portion 35, which ears snap into groove 26 in end 25 of the hose supporting portion 23 to lock the attaching portion 35 in secured relationship with the hose supporting portion 23. End 37 of the attaching portion 35 is further provided with a guide projection 39 which cooperates with longitudinal groove 27 of hose supporting portion end 25 to retain the attaching portion 35 in a preselected rotational relationship relative to the axis of the coupler 13.

Outer portion 32 of connector 16 is juxtaposed to the periphery of attaching portion end 36. To provide additional support of the connector 16 on coupler 13, a fastener 40 such as a rivet is passed through the outer portion 32 of connector 16 and the confronting wall of attaching portion end 36, as best seen in FIGURE 3. The inner portion 31 of the connector 16 is retained in recess 29 by an overlying annular outer portion 41 of a tubular enclosure 42. The inner end 43 of the enclosure has substantial longitudinal extent and surrounds the hose supporting portion 23 and the end of the hose 11 carried thereon. As best seen in FIGURE 3, sufficient clearance is provided between end 43 and the end of hose 11 to permit extension of wires 12 from the hose to the connector 16.

To lock the attaching portion 35 releasably in intake 14 of the vacuum cleaner suction unit 15 a spring catch 44 is secured to the attaching portion outer end 36. The catch includes a leaf spring support 45 secured at one end by a fastener 46 such as a rivet to the inner surface of the tubular wall of attaching portion end 36. An operating button 47 is fixed to the midportion of the spring support 45 and extends outwardly through an opening 48 in the wall of end 36. A retainer 49 is also secured to the inner surface of the wall to limit the inward movement of the spring support. At its outer end, the spring support is provided with a catch lug 50 which projects movably through an opening 51 in the wall of end 36 to project into a corresponding opening 52 in intake 14 by the biasing action of spring support 45 when the attaching portion 35 is inserted into intake 14.

As shown in FIGURES 1 and 3, female connector 17 of the suction unit 15 is superposed to intake 14 in position to receive the terminal prongs 34 of the male connector 16 when the attaching portion 35 of coupler 13 is connectedly associated with intake 14. Thus, the coupler 13 may be readily associated with the suction unit 15 to provide both an air flow connection and an electrical connection therebetween. As the electrical connector 16 is secured to the coupler 13, strains on the connector, such as may occur during a separation of the hose assembly 10 from the suction unit 15, are absorbed by the coupler instead of the wires 12, substantially extending the useful life of the hose assembly.

Turning now more specifically to FIGURES 1, 6 and 7, coupler 18 is seen to comprise a device generally similar to coupler 13. The attaching portion 53 of coupler 18 differs somewhat from the attaching portion 35 of coupler 13 in the provision of a tapered nose 54 at the outer end of attaching portion 53 and the provision of another form of spring catch 55. Spring catch 55 comprises an annular spring 56 extending approximately 270° concentrically within the tubular attaching portion 53 and provided adjacent one end with a catch lug 57 projecting through a suitable opening 58 in the wall of the attaching portion 53. The outer surface 59 of the catch lug 57 is rounded to have readily releasable locking coaction with a complementary recess 60 in the tubular

end 19 of the floor tool. Thus, when the attaching portion 53 of coupler 18 is inserted into the tubular end 19, spring catch 55 maintains the hose assembly 10 in association with tubular end 19, while permitting a ready disassociation therefrom when desired.

Female connector 20 associated with coupler 18 is preferably similar to inner portion 31 of male connector 16. Female connector 20 is disposed substantially fully within the outer end 141 of the surrounding enclosure and is retained in association with coupler 18 by its fit in recess 129 thereof. Thus, the association of hose assembly 10 with the end 19 of the floor tool wand is generally similar to the association thereof with the suction unit 15, concurrent air flow and electrical connection being made and broken therebetween in a facilitated manner. Strains on the connector 20 are absorbed by the coupler 18 rather than by the wires 12, similarly effecting substantial extension of the useful life of the hose assembly.

In certain instances, such as where the female connector of the suction unit 15 is not directly superposed to the intake, the outer portion of the male connector associated with the hose assembly may comprise a plug member 61 carrying the terminal prongs 34 and connected to the inner portion 31 of the connector by a flexible cable 62. This form of the invention is illustrated in FIGURE 8. It should be noted that here again the attachment of the inner portion 31 of the connector to the coupler assures that the coupler will absorb the strains on the connector to preclude the transmission thereof to the wires 12 associated with the hose.

Having described our invention as related to the embodiments shown in the accompanying drawings, it is intended that the invention be not limited by any one of the details of description, unless otherwise specified, but rather be construed broadly within its spirit and scope as set out in the accompanying claims.

The embodiments of the invention in which an exclusive property or privilege is claimed are defined as follows:

1. A coupling device for connecting one end of a vacuum cleaner air hose having integral electrical conductors to a vacuum cleaner apparatus, comprising: a tubular coupler having a first portion fixedly connected to the end of the air hose and provided with a recess means having first retaining elements, and a second portion attached to said first portion for removable association with the vacuum cleaner apparatus; an electrical connector having an inner portion with second retaining elements fitted into said recess means, said first and second retaining elements being complementary for retaining said connector portion on said coupler first portion, said connector having an outer portion secured to said second portion of the coupler; a pair of electrical connecting elements exposed for access from outside said coupler outer portion; means in said electrical connector electrically connecting said pair of elements to said hose electrical conductors; and enclosing means on said coupler overlying said connector inner portion recess means to aid in retaining said inner portion in said recess means.

2. The device of claim 1 wherein said first retaining elements comprise shoulders forming a part of said recess means, said second retaining elements comprise shoulders forming a part of said connector inner portion, and said enclosing means comprises a tubular enclosure around said coupler first portion.
